CARBURETER FOR INTERNAL-COMBUSTION ENGINES.

1,080,815.

Specification of Letters Patent.

Patented Dec. 9, 1913.

Application filed November 11, 1911. Serial No. 659,769.

To all whom it may concern:

Be it known that I, ERNEST PERCIVAL EVEREST, a subject of the King of Great Britain, residing at Coventry, in the county 5 of Warwick, England, have invented certain new and useful Improvements in Carbureters for Internal-Combustion Engines, of which the following is a specification.

This invention relates to spray carbureters 10 for use on internal combustion engines and has for its object to provide an improved form of carbureter of the single lever type. Carbureters of this type embody a variable air inlet, an adjustable carbureted air outlet, and a variable jet device, all controlled by a single lever so that the passages are, as a rule, increased or decreased simultaneously.

In actual practice, to cope with different 20 conditions the constitution of the mixture has to vary in order that good results may be obtained. Thus for slow running a slightly richer mixture is necessary than at other times, and with different engines the 25 richness varies differently throughout the range of movement of the control lever. This calls for a sensitive means of adjustment of the size of the fuel outlet in relation to the air and gas passages, and it is 30 to provide such improved means of adjustment that is the object of this invention.

In the accompanying drawings, Figure 1 is a central vertical section through part 35 of a carbureter constructed in accordance with this invention. The float chamber is omitted in this view for simplicity as it forms no part of the invention. Fig. 2 is a similar view at right angles to Fig. 1, and showing the float chamber. Fig. 3 is a plan 40 view of part of the jet tube showing the jet holes. Fig. 4 is a transverse section of the same, while Fig. 5 is a view corresponding to Fig. 3 showing a modification. Fig. 6 is a longitudinal section showing a modification; Fig. 7 is a similar view showing the parts in the position in which air alone is 45 admitted to the engine, and Fig. 8 is a plan view showing on an enlarged scale part of a jet tube with outlet holes of different sizes.

50 Like letters indicate like parts throughout the drawings.

In the construction illustrated, the fuel

jet consists of the tube A projecting into the carbureting chamber B. This tube is normally fed with petrol maintained at a 55 constant level by a float C or the like. In the upper side of the tube A the fuel outlet holes D are formed, it being understood that these are relatively small and that they are only made in part of the length of the tube. 60 Upon the outside of the tube a slide is arranged, this preferably taking the form of a sleeve held down by any suitable spring E, the sleeve being, if desired, constructed of some suitable anti-friction bearing metal, 65 such as white metal. In the construction illustrated the sleeve is made in two parts F and G adjustable in relation to one another. For instance, the sleeve part G may screw into the outer part F. It will be 70 understood that as the complete sleeve is moved along the tube A the holes D are covered or uncovered so that any desired jet outlet may be obtained.

The carbureting chamber is provided with 75 inlet and outlet ports H and J and over these slides a piston K which fits snugly within the carbureting chamber and takes a bearing on the plain part A² of the jet tube, for which purpose it is provided with 80 a tubular extension K² which forms a bearing part. It is also connected to the jet slide so that the two move together. The bearing part K² of the piston may be guided in part of the carbureting chamber and terminates 85 in any suitable device enabling the piston to be moved. For example, as shown, it may be provided with an eye to which may be attached a rod or wire. It will be gathered that as the piston is moved the jet 90 slide is moved, and preferably these are arranged so that the ports H and J and the jet outlets D are opened and closed together.

It will be seen that by a variable jet of 95 this type any desired results may be obtained as the increase or decrease in the effective jet outlet need not be proportional to the movement of the slide and can easily be varied. Thus the jet outlets may be 100 larger or more numerous at one point than at another, see Figs. 3 and 8, so that at certain positions of the throttle richer or weaker mixtures may be obtained. Again,

22
by adjusting the slide parts F and G a simple temporary adjustment may be obtained.

Conveniently the tube A is bored eccentrically, see Fig. 4, so that the wall is of small thickness at the top and the outlet passages formed by the holes D consequently short. The petrol level is arranged at or about the top of the outlet passages and it is not necessary that the level be maintained by a float as the slide may be adapted to completely cut off the outlets so as to constitute a valve. The spring E maintains a liquid-tight joint between the slide and the jet tube and a gas-tight one between the throttle face of the outlet. The spring forces the jet slide downward on to the jet tube and the throttle piston upward so as to maintain a gas-tight joint on the upper or outlet side of the throttle at all times if required.

If desired, the outlets may be formed of angular cuts see Fig. 5, so that a continuous or nearly continuous increase in the jet outlet can be obtained as the slide is moved longitudinally.

The angle of the slits may vary as shown roughly in Fig. 5 so that the area exposed may bear a suitable ratio to the corresponding port opening uncovered by the piston. If the port opening is a constant one, as may be obtained by making the openings rectangular, for the angular slits L a single longitudinal slit may be substituted. If desired the jet tube A may be made relatively large in diameter, and through the center of it longitudinally may be arranged a tube see Z, Fig. 6, for the passage of some heating medium. This tube would be provided with unions Y or similar connections at each end so as not to interfere with the accessibility of the carbureter. It will be understood that the heating surface provided will be very large in relation to the jet tube which is of considerable advantage where fuels of heavy specific gravity are used. When such a heating tube is used the rod or the like by which the piston is moved may be arranged to one side.

In the particular construction of carbureter described it is obvious that the piston throttle and jet slide may be operated by separate levers.

Preferably the carbureter is so constructed that the piston throttle may be moved beyond its closed position so as to partially or wholly expose the ports but not to expose the jet outlets.

In Fig. 1 the piston is moved to the left to close the ports, but further movement beyond the position in which all the jet outlets D are closed may be imparted to the piston to open up the ports on the right hand side and allow the passage of air alone, which is of great utility.

65 It will be seen that by this invention a

very simple form of variable jet is provided in which very different results can be easily obtained without changing the parts, although the jet tubes may be made easily removable and interchangeable.

What I claim as my invention, and desire to secure by Letters Patent, is:—

1. In a spray carbureter, the combination of a spray chamber, a fuel supply tube projecting into said spray chamber, fuel outlets in the upper surface of said tube, a slide mounted on said upper surface and adapted to cover and uncover said fuel outlets, and a spring holding said slide on to said jet tube and maintaining a liquid tight joint 80 between said slide and the upper surface of said tube substantially as set forth.

2. In a spray carbureter, the combination of a spraying chamber, a throttle valve movable in said chamber, a fixed fuel tube projecting into said chamber, fuel outlets in the upper surface of said tube, a slide mounted exteriorly on said tube and adapted to cover and uncover said fuel outlets, a spring arranged between the slide and the throttle 90 valve and exerting downward pressure on the slide to maintain a close joint between the latter and the fuel tube, and an adjustable connection between said slide and said throttle valve.

3. In a spray carbureter, the combination of a spraying chamber, an air inlet to said spraying chamber, a gas outlet from said spraying chamber, a throttle valve adapted to cover and uncover said inlet and outlet, 100 a fuel tube projecting into said chamber, fuel outlets in the upper surface of said tube, a slide mounted on said tube, and adapted to cover and uncover said fuel outlets, an adjustable connection between said slide and 105 said throttle valve, and a spring between said slide and the throttle valve, substantially as set forth.

4. In a spray carbureter, the combination of a spraying chamber, an air inlet to said spraying chamber, a gas outlet from said spraying chamber, a throttle valve adapted to cover and uncover said inlet and said outlet, a fuel tube projecting into said chamber, fuel outlets in the upper surface of said tube, an 115 inner sleeve mounted on said tube, an outer sleeve having an adjustable connection with said inner sleeve, a connection between the said outer sleeve and the throttle valve, and a spring between said outer sleeve and the 120 throttle valve, substantially as set forth.

5. In a spray carbureter, the combination of a spraying chamber, an air inlet to said spraying chamber, a gas outlet from said spraying chamber, a throttle valve adapted 125 to slide across said spraying chamber and uncover said inlet and outlet, a fuel tube projecting into said chamber, an eccentric passage in said fuel tube, fuel outlets therefrom, an inner sleeve adapted to slide on 130

said tube, an outer sleeve having a screwed connection with said inner sleeve, a connection between said outer sleeve and the throttle valve, and a spring between said outer sleeve and the throttle valve, substantially as set forth.

In testimony whereof I have signed my

name to this specification in the presence of two subscribing witnesses.

ERNEST PERCIVAL EVEREST.
